UNITED STATES PATENT OFFICE

109,170

DESIGN FOR A TOILET HINGE

Edward J. Witherell, Springfield, Mass., assignor to C. F. Church Mfg. Co., Willimansett, Mass.,
a corporation of Massachusetts

Application June 9, 1937, Serial No. 69,757

Term of patent 7 years

To all whom it may concern:

Be it known that I, Edward J. Witherell, a citizen of the United States, residing at Springfield, in the county of Hampden and State of Massachusetts, have invented a new, original, and ornamental Design for a Toilet Hinge, of which the following is a specification, reference being had to the accompanying drawing, forming a part thereof.

Fig. 1 is a side elevation of a toilet hinge showing my new design;

Fig. 2 is a front elevation of the same;

Fig. 3 is a side elevation of the hinge showing the hinge plate swung into view from behind the hinge support; and

Fig. 4 is a section taken on the line 4—4 of Fig. 1 and shows the form of section used to assist in obtaining a streamline effect.

I claim:

The ornamental design for a toilet hinge substantially as shown and described.

EDWARD J. WITHERELL,
